JAMES DEANS CUMMING, OF COPPER CLIFF, ONTARIO, CANADA.

SUPPORT FOR REFLECTORS.

1,295,701.

Specification of Letters Patent. Patented Feb. 25, 1919.

Application filed September 14, 1917. Serial No. 191,440.

To all whom it may concern:

Be it known that I, JAMES DEANS CUMMING, of the town of Copper Cliff, in the district of Sudbury, in the Province of Ontario, Canada, have invented certain new and useful Improvements in Supports for Reflectors, of which the following is the specification.

My invention relates to improvements in supports for reflectors particularly adaptable to parabolic reflectors and the object of the invention is to devise simple means for supporting a reflector so that it may be adjustably swung around a center coinciding with the focal point of the reflector and the center of intensity of a stationary light source and it consists essentially of the following arrangement and construction of parts as hereinafter more particularly explained.

Figure 1, is a perspective view of my support showing a reflector carried thereby, the reflector being in vertical section.

Fig. 2, is a vertical section through Fig. 1 with the major portion of the reflector broken away.

Fig. 3, is a plan view similar to Fig. 2.

In the drawings like letters of reference indicate corresponding parts in the various figures.

1 indicates a burner head provided with a horizontally extending tubular portion 1^x having a threaded exterior portion at its outer end. 2 indicates the burner, which is secured in the tubular portion 1 and from which a horizontally directed flame 2^x extends when the burner is lighted, the center of intensity of the flame 2^x being indicated by a cross 3.

4 indicates a parabolic reflector, which is mounted so that the focal point of the reflector coincides with the center of intensity 3 of the light source represented by the flame 2^x.

It will be readily understood that when using a reflector or more particularly a parabolic reflector with any light it is very desirable to keep the center of illumination as near the focal point of the reflector as possible. The reason for this is that to secure a maximum illumination the rays of light must be reflected from the surface of the reflector in a beam of parallel rays.

A parabolic reflector from its peculiar shape reflects all rays of light originating at its focal point in such a beam. Since

the focal point of a parabola is of no magnitude it is apparent that a light of any appreciable size can not be contained therein and, therefore, perfect reflection can never be obtained. If, however, the center of intensity of the light or flame be kept as close as possible to the focal point of the reflector the maximum efficiency of reflection attainable will be obtained.

In order to swingably mount the reflector so as to obtain the above result, that is, keep the center of swing of the reflector, center of light source and the focal point of the reflector coincident I have provided the following means for mounting the reflector upon the burner.

5 indicates a gland which is provided with an internal thread, which is screwed on to the external thread of the tubular portion 1^x of the burner. The gland 5 is also provided with an external thread 5^x. 6 and 7 indicate lugs, which extend out from the diametrically opposite sides of the gland in proximity to its outer end or that end of the gland next to the burner 2. 4^x indicates a slot, which is formed in the inner end of the reflector 4 and is vertically disposed. 8 indicates a bracket, which is secured to the reflector 4 at each end of the slot 4^x, such bracket being provided with arms 9, 10, 11 and 12 extending outwardly from the cross bars of the bracket.

15 and 16 indicate arc-shaped bar portions, the bar portion 15 being formed integral with the arms 10 and 11 and the bar portion 16 with the arms 9 and 12. The bar portions 15 and 16 are arc-shaped in form and concentric with the focal point of the reflector 4 and the center of illumination of the flame 2^x. 17 indicates an internally threaded annular nut, which is screwed upon the gland 5 and provided with wings 18 and 19 by which the nut is screwed into position.

When it is desired to attach the reflector in position all that it is necessary to do is to screw the nut 17 upon the gland 5, the arc-shaped bar portions 15 and 16 being inserted between the nut and the diametrically extending lugs 6 and 7.

When it is desired to adjust the angle of the reflector 4 all that it is necessary to do is to loosen the nut 17 and swing the reflector to the desired position. As the arc-shaped portions 15 and 16 are concentric with the center of light source formed by the flame 2^x, which corresponds also to the focal point

of the reflector, the center of intensity of illumination always coincides with such focal point at any position to which the reflector is swung.

5 With a reflector, which is rigidly fixed to the source of light, it has always been necessary to swing both the reflector and source of light to change the direction of the light rays. By my reflector holding device the 10 direction of the rays of light may be changed without moving the source of light or removing the center of intensity of the light from the focal point of the reflector.

Although I have described my invention 15 as particularly adaptable to a parabolic reflector it will, of course, be understood that it may be used with any other type which does not throw parallel rays of light, the object being no matter what type of reflector 20 is used that when the reflector is swung so as to direct the beams of light at any desired angle that the center of swing of such reflector coincides with the center of illumination.

25 It will be understood that the arc-shaped bars 15 and 16 are so disposed as to form sectors, the centers of which are located at each side of the center of illumination so that the line joining these centers would pass 30 through the center of illumination. By forming the slot 4^x as above described the flame 2^x passes horizontally from the burner

through the back of the reflector into the interior thereof, the slot being of such dimensions that the flame passes therethrough no 35 matter at what angular position the reflector is set within the limits desired and so that the center of the flame coincides with the focal point of the reflector.

What I claim as my invention is: 40

1. The combination with the burner arm, 45 of a parabolic reflector having an arc-shaped vertically disposed slot in the back thereof, arc-shaped bar portions concentric with the focal point of the reflector and carried by the reflector and clamping means carried by the burner arm designed to engage each inner and outer edge of the bar portions to secure them in position.

2. The combination with the burner arm, 50 of a parabolic reflector having an arc-shaped vertically disposed slot in the back thereof, arc-shaped bar portions concentric with the focal point of the reflector and carried by the reflector, a member carried by the burner arm having radially extending lugs adapted to extend against the inner edge of the arc-shaped bars, and a clamping screw designed to bear against the outer edge of the arc-shaped bars. 55

JAMES DEANS CUMMING.
